STRAIGHTEDGE AND PAPER CUTTER

Harry Taran, Detroit, Mich.

Application May 9, 1950, Serial No. 161,036

4 Claims. (Cl. 164—73)

1

The present invention relates to paper cutters, and more particularly to a paper cutter, primarily, but not exclusively, adapted for use in cutting wallpaper, and which is simply, but compactly built to permit economic production thereof while insuring that wallpaper can be cleanly cut therewith in a perfectly straight line.

When it is necessary to cut wallpaper while hanging the wallpaper in a room or the like, the paper must be cut cleanly and in a perfectly straight line in order that the finished work will give a pleasing appearance. If a strip of wallpaper is raggedly cut or is cut awry, such paper normally cannot be used and is wasted.

The conventional paper cutters heretofore used comprise straight edges having cutter members slidably mounted thereon. These prior paper cutters have not proven entirely satisfactory, since the cutter members either have a tendency to wobble on the straight edges or the cutter blades do not have a sufficiently sharp edge at all times to insure that the paper will be cleanly cut.

Accordingly, it is an object of the present invention to provide a paper cutter having a cutter member slidably mounted on a straight edge and which is constructed and arranged to prevent the cutter blade from losing contact with the edge of the straight edge when the cutter member is slidably moved thereon to insure cutting wallpaper or the like in a straight line.

It is a further object of the present invention to provide a paper cutter adapted to use conventional razor blades for cutting wallpaper, and which blades are mounted on a pivotal support member, enabling the operator to selectively use either of two cutting edge corners of said blade, and further which is constructed to permit worn blades to be easily replaced by unworn blades so that the operator will always have readily available a sharp cutting blade on the paper cutter.

It is still another object of the present invention to provide a paper cutter which is light in weight permitting it to be easily handled by the user thereof, and which can be cheaply but sturdy constructed to provide an accurate cutting instrument at low cost.

Other objects of this invention will appear in the following description and appended claims, reference being had to the accompanying drawings forming a part of this specification wherein like reference characters designate corresponding parts in the several views.

In the drawings:

Fig. 1 of the drawings is a rear elevational view

2

of the cutter member of the present invention with a fragmentary portion of the straight edge shown in phantom.

Fig. 2 is a sectional view taken on the line 2—2 of Fig. 1 showing the mounting arrangement of the cutter member on the straight edge.

Fig. 3 is a perspective view of the straight edge and the cutter member mounted thereon.

Fig. 4 is a fragmentary view of the paper cutter showing a portion of the straight edge and a front elevation of the cutter member mounted thereon.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings, an embodiment of the present invention can be seen comprising a straight edge 10 having a cutter member 12 slidably mounted thereon. The straight edge 10 has a track 14 on the upper surface and adjacent one of the edges thereof on which the cutter member 12 is adapted to ride.

As can be seen in Figs. 2 and 3, the track 14 is made of a pair of members 16 and 18 which together with the upper surface of the straight edge 10 form an inverted T-shaped slot into which a depending portion of the cutter member 12 extends, permitting said cutter member 12 to be slidably movable on the straight edge 10 as will be more fully described hereinafter. It is preferred to make the straight edge 10 of a wooden section 22 having a channel section 24 made of aluminum extending around the one edge thereof. However, if desired, other suitable sturdy lightweight materials may be used.

The outer edge of the channel member 24 has a shoulder portion 26 against which the cutting blade of the cutter member 12 is adapted to slidably engage during operation of the paper cutter. Each of the ends of the track 14 has an insert member 28 therein to prevent the cutter member 12 from running off the end of the straight edge 10.

The cutter member 12 includes a carrier 30 having a T-shaped depending portion 32 which is suitably shaped to fit snugly but slidably within the T-shaped slot of the track 14. This construction permits the carrier 30 to slide longitudinally of the straight edge 10, and will pre-

vent wobbling of said carrier 30 with respect to the straight edge 10.

The upper surface of the carrier 30 has a rounded shoulder 33 and a shaft 34 in axial alignment with said rounded shoulder 33 on which a cutter support member 36 is pivotally mounted. The cutter support member 36 has a flange 36a in which a slot 36b is cut to form a journal which is saddled over the rounded shoulder 33. The cutter support member 36 is held against axial movement on the shaft 34 by the shoulder portion 38 and the washer 40 which is secured to the carrier 30 by the screw 42. As can be seen in Fig. 2 of the drawing, the washer 40 extends into the annular slot 44 of the support member 36 to hold the latter against the shoulder 38. However, it should be understood that sufficient clearance is provided between the shoulder 38 and the support member 36 to permit the latter to be pivoted on the shaft 34.

The support member 36 has a depending wall portion 46 which has its inner surface recessed for receiving a razor blade 48 or the like therein. The razor blade 48 is held in a fixed position on the depending wall portion 46 by means of the screw 50.

The depending wall portion 46 extends below the upper edge of the shoulder 26 so as to maintain the razor blade 48 in firm sliding engagement with said shoulder portion 26. The recess above the shoulder 26 is sufficiently great to provide clearance for the head of the screw 50 for pivotal movement of the support member 36 with respect to the straight edge 10.

When the paper cutter is not in use, or when it is being transported from one place to another, the cutter member 12 can be locked against movement on the straight edge 10 by means of the locking screw 54 which extends through the carrier 30 and can be screwed into tight engagement with the member 16 of the track 14.

From the above description, it is believed to be clear that the cutter member 12 can be slidably moved on the straight edge 10 and no wobble of the cutter member 12 with respect to the straight edge 10 can occur. The former is closely fitted to the latter so that there can be no movement except in a longitudinal direction. The carrier 30 and support member 36 of the cutter member 12 are made of aluminum so that the entire paper cutter is light in weight and easy to handle. By virtue of the pivotal mounting of the support member 36, either of the lower edge cutting corners of the razor blade can be used for cutting wallpaper.

When both of the lower cutting edge corners of the razor blade have become sufficiently dull so that the wallpaper will not be cleanly cut thereby, the razor blade can be easily and quickly replaced merely by removing the screw 42, thereby removing the support member 36 from the carrier 30, and then the screw 50 can be removed and a new blade inserted in place of the worn one. Any razor blade discarded after having been used for shaving purposes or the like is suitable for use with the paper cutter, and it is believed to be readily understood that there will be no operating cost incurred in using this cutting instrument.

Thus it can be seen that the present invention

provides a paper cutter which can be used to cut wallpaper in clean straight lines and which is simply and ruggedly constructed, permitting it to be produced at low cost and still provide an instrument for performing accurate work. The paper cutter is adapted to use conventional razor blades which have been discarded, and it is designed to permit use of either of two cutting edge corners before substituting an unworn blade for a worn one. Further, the paper cutter is light in weight permitting it to be easily handled and transported from place to place.

Having thus described my invention, I claim:

1. A paper cutter comprising a straight edge having a carrier slidably mounted in a tongue and groove relationship on the upper surface and adjacent one edge thereof, said carrier having a cylindrical portion on its upper surface normal to the plane of said edge, said portion projecting beyond said plane as a shaft, a cutter support member pivotally mounted on said shaft and having a bearing surface saddled over said cylindrical portion, said cutter support member overlapping said one edge with the overlapping surface being recessed to receive a cutter blade, and a cutter blade secured in said recessed portion so that it will be in sliding engagement with said one edge.

2. A paper cutter comprising a straight edge having a carrier slidably mounted in a T-shaped tongue and groove relationship on the upper surface and adjacent one edge thereof, said carrier having a cylindrical portion on its upper surface normal to the plane of said edge, said portion projecting beyond said plane as a shaft, a cutter support member pivotally mounted on said shaft and having a bearing surface saddled over said cylindrical portion, said cutter support member overlapping said one edge with the overlapping surface being recessed to receive a razor blade, a razor blade secured in said recessed portion so that it will be in sliding engagement with said one edge and with its cutting edge lowermost so that the cutter support member can be pivoted to bring either end of the cutting edge into engagement with paper to be cut.

3. A paper cutter as claimed in claim 2 wherein said cutter support member is retained in its pivotally mounted position by a thrust member held against the end of said shaft and a portion of said support member by a screw threadedly connected to said shaft.

4. A paper cutter as claimed in claim 3 wherein said edge of the straight edge has a groove therein, and a single screw secures the razor blade in said recessed portion, the head of said screw extending into said groove which provides clearance therefor.

HARRY TARAN.
